RESTRICTOR TUBING

John Karmazin, Huntington, Ind., assignor to
General Motors Corporation, Dayton, Ohio, a
corporation of Delaware

Application May 18, 1936, Serial No. 80,255

1 Claim. (Cl. 138—44)

This invention relates to refrigerating apparatus.

An object of this invention is to provide an improvement in refrigeration which includes a relatively long and small diameter tube which is adapted to interpose the necessary restriction between the high side and the low side of the refrigerating system.

Further objects and advantages of the present invention will be apparent from the following description, reference being had to the accompanying drawing, wherein a preferred form of the present invention is clearly shown.

In the drawing:

Fig. 1 is a diagrammatic representation of a refrigerating apparatus embodying features of this invention;

Fig. 2 is a view, partly in cross-section of a step in the manufacture of the tubing;

Fig. 3 is a view similar to Fig. 2, but showing a modified form of the invention;

Fig. 4 is a view, partly in cross-section, of the tubing in partly finished form; and

Fig. 5 is a diagrammatic view of a furnace in which the tubing may be heated and brazed.

Heretofore tubes of small diameter and relatively great length have been interposed between the high side and the low side of a refrigerating system, as a substitute for automatic expansion valves, floats and the like. However, these prior uses have been open to the objection that the tubing cannot be made of uniform diameter in large quantities so that a uniform product can be obtained in mass production.

According to this invention, however, a restrictor tube is provided which interposes uniform restrictions on the flow of refrigerant and in which the tubing can be manufactured in large quantities with absolute uniformity.

This invention is particularly applicable to refrigerating systems having high sides and low sides. The high side may include a compressor unit 10 discharging into a condenser unit 11. The liquefied refrigerant then flows through the restrictor tubing 12 to the evaporator 13. From thence the evaporated refrigerant returns through the pipe 14 to the compressor unit 10.

In modern household refrigerators, the above system may take the specific form shown in the drawing in that the compressor 10 includes a motor and compressor sealed within the casing 15. The condenser 11 may include a series of loops through which air is circulated by means of the motor fan 16. The condensed refrigerant is gathered in the receiver 17. The tube 12 may

be of uniform dimensions throughout its length, and, if excessively long, may be coiled at 18. The evaporator 13 may be provided with one or more freezing shelves 19 having passageways 20 through which the refrigerant flows before it enters a lower header 21 which distributes refrigerant to the upwardly directed loops 22 discharging into headers 23 which are joined by the branches 24 discharging into the pipe 14.

The motor-compressor unit 10 generally includes a type of motor which runs at a constant speed whereas the condenser 11 is subject to varying degrees of cooling depending on the temperature of the atmospheric air flowing through the condenser. On a cool day therefore, the condenser 11 operates at a relatively cool temperature and the refrigerant pressure on the high side of the system is relatively low. On warm days, on the other hand, the refrigerant pressure is relatively high on the high side. The tendency, therefore, is to cause too much refrigerant to flow through the restrictor 12 on warm days, and if the tube is not properly calibrated, the liquid refrigerant in the receiver 17 is emptied and gaseous refrigerant tends to flow through the tube 12. When this occurs, the efficiency of the refrigerating apparatus is greatly lessened with consequent high current consumption for the refrigeration produced.

It is well-known that if tubes of proper length and cross-section are provided, the restriction of the tube 12 can be properly balanced so that this flow of gaseous refrigerant can be avoided and yet a sufficient flow of liquid refrigerant can be insured at all room temperatures for the refrigeration demands. In ordinary household refrigerators, a tube of about .035" internal diameter and from 10 to 14 ft. in length has been found satisfactory. However, it is extremely difficult to manufacture a tube of such small internal diameter in large quantities for installation in a cabinet or the like. According to my invention a tube is provided which imposes a more uniform restriction and which may be cheaply manufactured in large quantities.

In manufacturing my tubing, steel wire of from .018" to .023" in diameter is wound on the rotating member 30 of the usual spring coil machine to produce a wire coil in which the individual loops 31 are placed under natural tension tending to hold them together. Thereafter, a wire 32 of bonding material is placed in the spring tube and the same is passed through a heating zone or furnace 33 in which a reducing atmosphere, such as hydrogen, is maintained.

The tube is heated to a temperature sufficient to cause the copper wire 32 to flow into the interstices 34 between the loops 31 and braze the same together hermetically. Preferably the tube is maintained in a horizontal position through the heating zone and yet the bonding material or copper from the wire 32 rises by capillary attraction between the loops 31 and brazes the entire tube. The tendency is to provide a tube 10 which is thoroughly copper coated both inside and outside throughout its area. This produces a very clean tube of uniform restriction.

In order to provide a tube which may be even more readily bent, I may wind two or more steel wires 35 and 36 on the coil machine 37 to produce the spring coil 38. At the same time a reinforcing wire 39 is wound over the wires 35 and 36. This wire 39, however, may be omitted if desired. By winding the two wires 35 and 36 20 the loops of the wires are at a more acute angle and the tube, after it has been brazed in the same manner as the tube 31, is very easily bent without danger of rupture. It is to be understood, that the tube made in accordance with 25 Fig. 3, is brazed in the same manner as that described for the tube shown in Fig. 2.

The internal spiral ridges formed by my tubing provide a more efficient restricting action than a tube of smooth internal bore. Oil slugs, 30 which generally are present in refrigerating sys-

tems of this kind, are forced more easily through the tubing. These ridges also tend to provide a more efficient restriction against the flow of gas through the tubing and thus tends to prevent loss of efficiency in this respect.

While I have described the tubing as made of steel wire bonded together with copper, it is to be understood that other materials may be used for the same purpose. Thus the wires which form the loops of the tube may be of copper, and 10 the bonding material may be any of the well-known solders adapted to bond copper. Such solders may be in the form of wire if desired.

While the form of embodiment of the invention as herein disclosed, constitutes a preferred 15 form, it is to be understood that other forms might be adopted, all coming within the scope of the claim which follows.

What is claimed is as follows:

Restrictor tubing of small diameter for refrigerating apparatus comprising steel wire wound into the form of a spiral spring with the individual coils hermetically bonded together with cuprous bonding material while in a reducing atmosphere, the internal surfaces of said tubing presenting a series of turbulence producing corrugations, and the internal diameter being sufficiently small to afford proper restriction to the flow of refrigerant through the tubing.
